UNITED STATES PATENT OFFICE

133,708

DESIGN FOR A POWER DRIVEN HAND SPRAYER

Nicholas A. Constantine, Duluth, Minn.

Application December 1, 1941, Serial No. 104,418

Term of patent 7 years

To all whom it may concern:

Be it known that I, Nicholas A. Constantine, a citizen of the United States, residing at Duluth, in the county of St. Louis and State of Minnesota, have invented a new, original, and ornamental Design for Power Driven Hand Sprayers, of which the following is a specification, reference being had to the accompanying drawing, forming part thereof.

In the drawing:

Figure 1 is a side elevational view of a power driven hand sprayer, showing my new design.

Figure 2 is an end elevational view of Figure 1.

I claim:

The ornamental design for a power driven hand sprayer, as shown.

NICHOLAS A. CONSTANTINE,
